[57] CLAIM

The ornamental design for a front panel for a modular radio assembly, as shown and described.

DESCRIPTION

FIG. 1 is a top, front, right side perspective view of a front panel for a modular radio assembly showing our new design;

FIG. 2 is a left side elevational view thereof; and,

FIG. 3 is a bottom plan view thereof.

The rear view is unornamented.

FIG.1

FIG. 2

FIG. 3
